Adele Q. Freedman, New York, N. Y.

Application June 5, 1952, Serial No. 20,052

Term of patent 14 years

(Cl. D87—3)

To all whom it may concern:

Be it known that I, Adele Q. Freedman, a citizen of the United States of America, residing in New York, county of New York, and State of New York, have invented a new, original, and ornamental Design for an Embossed Plastic Sheet or Similar Article, of which the following is a specification, reference being had to the accompanying drawing, forming part thereof,

Fig. 1 is a plan view of an embossed plastic sheet or similar article showing my new design.

Fig. 2 is an edge view thereof.

A design unit is outlined by broken lines and is repeated as indicated.

I claim:

The ornamental design for an embossed plastic

sheet or similar article, substantially as shown and described.

ADELE Q. FREEDMAN.
